RESTAURANT BUILDING

Edwin H. Eichler, 910 Lake Shore Drive, Chicago, Ill.

Filed Sept. 22, 1964, Ser. No. 81,826

Term of patent 14 years

(Cl. D13—1)

Fig. 1.

Fig. 2.

FIGURE 1 is a perspective view of a restaurant building showing my new design;

FIG. 2 is a top plan view of the restaurant building shown in FIG. 1; and

FIG. 3 is an elevation view of the hidden side to the left in FIG. 1.

The dominant features of my design reside in the portions shown in full lines.

The ornamental design is substantially symmetrical about the longitudinal axis.

The ornamental design of my restaurant building is generally characterized by a wheeled circus-wagon facade simulating barred cages with convoluted ornamental borders.

I claim:

The ornamental design for a restaurant building, substantially as shown and described.
